[57] CLAIM

The ornamental design for ski boat pylon, as shown and described.

DESCRIPTION

FIG. 1 is a front elevational view of a ski boat pylon showing my new design, the rear elevational view being identical. The broken lines are for illustrative purposes only and form no part of the claimed design;

FIG. 2 is a side elevational view thereof, the opposite side being a mirror image thereof;

FIG. 3 is a top plan view thereof; and,

FIG. 4 is a bottom plan view thereof.

FIG. 3

FIG. 1

FIG. 2

FIG. 4
